UNITED STATES PATENT OFFICE.

WILLIAM M. BRITTEN, OF LOS ANGELES, CALIFORNIA.

OIL-BURNER.

1,102,387.

Specification of Letters Patent.

Patented July 7, 1914.

Application filed January 25, 1912. Serial No. 673,677.

To all whom it may concern:

Be it known that I, WILLIAM M. BRITTEN, a citizen of the United States, residing at Los Angeles, in the county of Los Angeles and State of California, have invented a new and useful Oil-Burner, of which the following is a specification.

The main object of the invention is to provide means for efficient vaporization of the oil in an oil burner, and for mixture of the vaporized oil with the air for combustion. By providing for such vaporization and mixture I am enabled to utilize comparatively heavy and cheap oils without the production of smoke or soot, and with maximum efficiency of combustion.

Another object of the invention is to provide means for forcibly driving the air through the vaporized oil to produce the mixture.

Other objects of the invention will appear hereinafter.

The accompanying drawings illustrate an embodiment of the invention, and referring thereto: Figure 1 is a vertical section of the oil burner. Fig. 2 is a section on line x^2-x^2 in Fig. 1. Fig. 3 is a section on line x^3-x^3 in Fig. 1. Fig. 4 is a plan view of one form of the vaporizing disk. Fig. 5 is a plan view of another form thereof. Fig. 6 is a vertical section showing the application of the vaporizing disk shown in Fig. 5.

The oil burner comprises a hollow body or base 1, serving as a casing and inclosing the rotary operating means, a cylindrical casing 2, extending upwardly from the base 1, an oil vaporizer and mixer 4, rotatably mounted within the casing 2, a fan 5 rotatably mounted within the casing 2 for forcing air through said oil vaporizer and a rotary motor or turbine 3 mounted in or on the casing 1 and connected to rotate said oil vaporizer and also connected to rotate said fan.

An oil supply pipe 7 communicates with a hollow arm or tube 8 extending inwardly from the wall of the casing 1, and provided at the center of said casing 1 with a screw threaded opening into which is screwed a vertical hollow stem or tube 10 which extends upwardly within the cylindrical casing 2. A sleeve 12 is rotatably mounted on said stem, being preferably supported at its upper end by a ball 14 resting on the top of a vertically projecting lug 15 on top

of said hollow stem, said sleeve 12 having a recess 16 for receiving said ball. The vertically extending lug 15 is formed with a transverse opening 17 for passage of oil from the bore of tube 10 and the upward extension 18 of the sleeve 12 is formed with openings 19 communicating with the opening 17 whereby the oil from the bore of tube 10 may flow out from the sleeve.

The oil vaporizer and mixer 4 is formed as a disk preferably dish-shaped with its concave face uppermost and having a series or plurality of perforations 20, the portions of said disk adjacent said perforations being preferably bent to form agitating wings for beating and mixing the vapor and air as the air passes through said openings or perforations, and the outer edge or periphery of said disk is also preferably fluted or convoluted for the same purpose. Said vaporizing disk 4 is clamped between a shoulder 23 on the sleeve 12 and the upper end of a sleeve 24, screwing on said sleeve 12 at 25 whereby the vaporizing disk is caused to 80 rotate with the sleeve 12. The disk 4 constitutes a revolving grate which is adapted to receive oil and on which the oil is gassified and its carbon burned.

The fan 5 is clamped on the sleeve 24 by 85 means of a nut 27 screwing on said sleeve 24 at 28 and clamping the hub portion 30 of said fan 5 against a shoulder 31 on sleeve 24. The lower portion of sleeve 24 is expanded to form a disk 33 on the lower face 90 of which are formed a series of turbine blades or buckets 35. A nozzle 37 is formed on or secured to the body or case 1 and is connected to a supply pipe 38 for water or other operating fluid, said nozzle being directed in such manner as to cause the jet therefrom to impinge on the turbine blades 35. A cover or partition plate 42 extends over the base or body 1, being supported, for example, by means of lugs 46 resting on 100 the shoulder 47 on said body 1, said cover extending inwardly adjacent to the turbine disk 33 so as to form, in connection with the body 1, an inclosure for the turbine and cause all the operating fluid for the turbine 105 to be retained within said inclosure. A drain pipe 46 leads from the lower part of the body 1 to drain off the water from the turbine, said body 1 being preferably conical or funnel shaped so as to drain the water to said pipe.

Fan 5 is located below the vaporizing

disk 4 and openings 49 are provided in the wall of casing 2, below the level of fan 5, so as to admit air to said casing below said vaporizing disk, such air being driven upwardly by the fan and forced through and past the vaporizing disk.

The portions of the vaporizing disk adjacent the openings therein may be bent upwardly as shown in Figs. 1 and 4 to serve 10 as discharge lips for conducting the vapor over the currents of air passing through the openings and for agitating or beating the air and vapor as they pass through the openings or, as shown in Figs. 5 and 6, the 15 portions of the disk adjacent said openings may be bent in various directions both downwardly and upwardly to increase the agitating effect.

The operation is as follows: Operating 20 fluid being admitted to the supply pipe 38, issues through the nozzle 37 and impinges on the turbine plates 35, causing rotation of the turbine. At the same time, oil or liquid fuel is admitted through the supply pipe 7, 25 and passes up through the tube 10 and out through the openings 17 and 19 onto the spreader or vaporizing disk 4. In starting the burner, gasoline or light oil is first admitted and burnt until the vaporizing disk 30 becomes red hot. The rotation of the vaporizing disk by the operation of the turbine is sufficiently rapid to cause the oil to be distributed or spread over the heated surface of the disk 4 and to be vaporized by the 35 heat of the disk. At the same time, the rotation of the fan 5 by the turbine causes a current of air to be drawn in through the openings 49 and forced upwardly through the cylindrical casing 2, past and through 40 the vaporizing disk and through the perforations and openings 20 therein, thereby thoroughly mixing the vaporized oil with the air. The curved portions of the vaporizing disk adjacent to the periphery of the 45 disk and adjacent to the openings 20 serve to beat or agitate the air and vapor at these points so as to insure mixing of the vapor with the air, the oil being vaporized by the heat of the disk due to the combustion directly above it, and being mixed and carried away by the current of air produced by the 50 fan. By providing a separate vaporizing device independent of the fan, I am enabled to provide for uniform distribution and 55 mixture of the vapor throughout the interior of the casing. This mixture burns immediately above the vaporizing disk and keeps the disk hot, said vaporizing disk being located below the top of the casing, so that the upper portion of the casing constitutes a combustion chamber and the flame therein heats the disk by direct contact therewith.

In the form of my invention shown in 60 Fig. 6, the vaporizing disk indicated at 4'

is formed with openings 20' with portions 21 adjacent to said openings bent at an angle to serve as beaters or agitators for the air, said portions being bent to form blades in this case, whereas in the form 70 shown in Figs. 1 and 4, the body of the disk is bent up adjacent each opening to form an agitating surface.

It will be noted on reference to Figs. 4 and 5 that the openings in the disk are arranged in staggered relation and at different distances from the center. The object of this is to supply the air in distributed manner to the oil vapor as it is vaporized and to cause combustion throughout the area of 80 the disk. By staggering the openings and bending their edges upwardly, the oil is forced to flow more uniformly over the disk and the air is supplied more uniformly to the oil vapor.

What I claim is:

1. In an oil burner, a casing, the upper part of which forms a combustion chamber, a vaporizing member rotatably mounted in said casing, in position to receive heat by 90 contact with the flame in said combustion chamber, said vaporizing member having openings, a fan rotatably mounted in said casing and adapted to force a current of air past the vaporizing member and through 95 said openings, means for supplying oil to said vaporizing member, and means for rotating said vaporizing member and fan.

2. An oil burner comprising a cylindrical casing having an air inlet, a vaporizing disk 100 rotatably mounted in said casing and dividing the interior of the casing into a combustion chamber above the disk, and an air receiving chamber below the disk, said disk being located in position to receive heat from the flame in said combustion chamber and 105 being provided with openings, a supporting shaft for said disk, oil supply means communicating through said shaft with the said disk to supply oil thereto, a fan connected to said shaft to rotate therewith, said fan being located between the inlet in said casing and said disk to force a current of air past and through said disk, and driving means connected to said shaft to rotate the same.

3. An oil burner comprising a cylindrical casing having an air inlet, a vaporizing disk 110 rotatably mounted in said casing and dividing the interior of the casing into a combustion chamber above the disk, and an air receiving chamber below the disk, said disk being located in position to receive heat from the flame in said combustion chamber, and 115 being provided with openings, a supporting shaft for said disk, oil supply means communicating through said shaft with the said disk to supply oil thereto, a fan connected to said shaft to rotate therewith, said fan being located between the inlet in said casing and said disk to force a current of air past 120

125

130

- and through said disk, and driving means connected to said shaft to rotate the same, said vaporizing disk having its portions adjacent said openings bent to act as agitators for the air and vapor.
4. An oil burner comprising a cylindrical casing having an air inlet, a vaporizing disk rotatably mounted in said casing and dividing the interior of the casing into a combustion chamber above the disk, and an air receiving chamber below the disk, said disk being located in position to receive heat from the flame in said combustion chamber and being provided with openings, a supporting shaft for said disk, oil supply means communicating through said shaft with the said disk to supply oil thereto, a fan connected to said shaft to rotate therewith, said fan being located between the inlet in said casing and said disk to force a current of air past and through said disk, and driving means connected to said shaft to rotate the same, said vaporizing disk having its portions adjacent said openings bent to act as agitators for the air and vapor, said vaporizing disk having its periphery fluted for the purpose set forth.
5. In an oil burner, a casing having an air inlet, a disk rotatably mounted in said casing and having openings arranged at different distances from the center and distributed
- around the disk, said disk being located within the casing and dividing the casing into a combustion chamber above the disk and an air inlet chamber below the disk, and said disk being in position to be heated by contact with the flame in the combustion chamber, a shaft carrying said disk, a fan carried by said shaft, means for rotating said shaft, and means for supplying oil to the central portion of said disk.
6. In an oil burner, a casing having an air inlet, a dish-shaped disk rotatably mounted in said casing and having openings arranged at different distances from the center and in staggered relation, said disk being located within the casing and dividing the casing into a combustion chamber above the disk and an air inlet chamber below the disk, and said disk being in position to be heated by contact with the flame in the combustion chamber, a shaft carrying said disk, a fan carried by said shaft, means for rotating said shaft, and means for supplying oil to the central portion of said shaft.

In testimony whereof, I have hereunto set my hand at Los Angeles, California this 14 day of September, 1911.

WILLIAM M. BRITTON.
